UNITED STATES PATENT OFFICE.

GEORGE H. MERKEL, OF BLUEFIELD, WEST VIRGINIA.

COMBINED PIANO BENCH AND MUSIC CABINET.

Application filed June 6, 1922. Serial No. 566,258.

To all whom it may concern:

Be it known that I, GEORGE H. MERKEL, a citizen of the United States, residing at Bluefield, in the county of Mercer and State 5 of West Virginia, have invented certain Improvements in Combined Piano Benches and Music Cabinets, of which the following is a full and complete specification.

My invention is an improvement in articles of furniture of that particular class in which the article is adapted to serve other purposes than that for which it is especially designed, in the present instance to provide a music cabinet or cabinets in connection 15 with a piano-bench.

The principal objects of my invention are to provide a combined piano bench and music cabinet in which the seat or seat portions of the bench may be tilted to a more or less extent for the convenience of the performer in playing the piano, and in which the performer may have easy access to the music cabinets without rising from the bench, the general structure being such that it will present 25 a very useful article of furniture of neat and ornamental appearance, strong and durable.

With these main objects in view my invention contemplates a construction of piano-bench in which the end portions thereof are in the form of boxes to provide music cabinets or compartments for sheet music, &c., below the top or seat of the bench with recesses or open spaces under that portion of the top between said cabinets at opposite sides of the bench, the top in the present instance being divided into several adjustable seat portions which may be tilted to a more or less extent and those over the compartments provided with hinged lids swinging upward independently for more convenient access to said compartments; all as herein-after fully described and more specifically set forth in the appended claims.

45 In the accompanying drawings:

Fig. 1 is a front elevation of a piano bench and music cabinet constructed in accordance with my invention.

Fig. 2 is a plan view thereof.

50 Fig. 3 is a vertical longitudinal sectional view through one end of the bench.

Fig. 4 is a plan view of one end of the bench with the seat portions broken away to show detail of construction.

Fig. 5 is a transverse sectional view 55 through the center of the bench.

Fig. 6 is an enlarged detail cross-sectional view through the central portion of the bench to show the means for supporting the seat sections.

60 Fig. 7 is a similar view through that portion of the top providing one of the seat sections above the compartments for the sheet music.

Fig. 8 is a detail view of the means employed for supporting the seat sections in tilted position.

Fig. 9 is a detail sectional view of the ratchet-plate.

Fig. 10 is a detail sectional view showing 70 the form of hinge-connection employed.

In carrying out my invention the bench is constructed to provide two similar box-like end portions 15, 15, rectangular in shape and spaced a suitable distance apart to accommodate a main seat section, hereinafter referred to, said boxes forming the music cabinets and are connected by a top 16 and partition 17, the latter being below the central portion of the top or seat to divide the intervening space between the boxes into opposite recesses under this portion of the seat of the bench, and the structure is preferably provided at its four corners with feet 18 for supporting the same above the floor, although of course the feet may be dispensed with if desired. In the present instance the box-like end portions of the bench are intended to provide receptacles or compartments for music sheets, and for convenience in orderly arranging the sheets of music therein said boxes are each provided with vertical partitions 19 held in place in the usual manner by engaging grooves in the opposite sides of the compartment; however, 80 85 90

95 as will be understood, any other arrangement may be provided to receive the music sheets, or to receive music-rolls, or other articles to be kept within the compartment. To give strength to the bench structure the boxes are reinforced at their lower ends by 100 a framework of strips or battens 20 and by

a baseboard or molding strip 21, the latter being continued along the lower edge of the partition 17 as shown in the drawings. Likewise the connection of the top or seat frame 16 of the bench to the box-like end portions or cabinets 15 is reinforced by ornamental molding strips 22 extending entirely around the upper part of the structure and slightly below said top or seat frame and across the upper part of the recesses between the boxes. The partition 17 terminates at its upper end on a plane with the lower edges of the molding strips 22, being braced by a cross-piece 23, and by reference to Figs. 3 and 4 it will be seen there is a rectangular framework for supporting the center adjustable seat section 26, hereinafter described, comprising strips 24 attached to the sides of the cabinets and opposite portions of the side rails of the top, the latter being recessed, at 25, to receive said seat section.

The top or seat of the bench is in the present instance provided with three independent and adjustable sections or seat portions including the center section 26 and end sections 28, 28, the latter being above and therefore serving to close the upper ends of the cabinets or compartments 15. The adjustable seat section 26 may be solid as indicated in Fig. 5 or composite as indicated in Fig. 6, in either instance being preferably reinforced by battens 26^a, and this seat section is hinged at one end, its front end, to the rail of the top frame of the bench in the manner shown in Fig. 10, in which the hinge comprises a pivot-pin 29 with an integral attaching-plate 30 fastened to the side piece of the cabinet, and a socket-plate 31 attached to the edge of the seat section with a hole through which the pivot-pin passes into a registering hole in the seat section. By this arrangement the seat section may be swung upwardly at its rear end to any desired inclination, and for the purpose of holding the same in an adjusted position it is provided underneath at both sides with a pivoted rack-plate or toothed pawl 32 adapted to engage a pin 33 projecting from the adjoining side of the cabinet, respectively, each swinging rack-plate being pivoted in a bracket 34 attached to the underside of the seat section and the engaging pin 33 located to dispose said ratchet-plate at an angle so that it may ride over the pin when the free end of the seat section is swung upward for engagement of any one of the teeth 35 with said pin according to the inclination or tilt desired. To provide for lowering the seat section by an automatic operation of the rack-plate the latter is provided at its outer end a suitable distance beyond the last engaging-tooth with a hook or catch-member 36 serving to limit the upward movement of the seat section, and in connection with this hooked stop there is a spring guard or lip 37 attached

by member 37^a thereof to one side of the rack-plate so that the lip will overlie all of the teeth but the first one with an intervening space sufficient to permit the pin to ride over said teeth, the outer end of said lip being curved inwardly to terminate near the edge of the rack-plate between the last engaging-tooth and hooked stop, whereby when the seat section is raised to its fullest extent the pin will pass under the lip by 75 forcing it outward and when said seat member is then lowered the pin will be guided over the outer surface of the lip free of the engaging teeth. As will be noted the length of the spring guard or lip is such with respect to the movement of the seat section that in lowering the latter the pin passes beyond the inner end of said guard or lip to again engage the edge of the rack-plate and teeth when the seat section is raised, and to 85 escape the projecting end of the pin 33 the connecting portion 37^a of the spring guard or lip is curved laterally, as shown in Fig. 9. By this arrangement the main seat section 26 may be adjusted at any desired inclination or tilt according to the length of the rack-plate and number of engaging-teeth at the edge thereof, and to lower said seat section it is necessary only to raise it to the limit and then lower or drop it. As the 95 seat portion fits snugly within the top frame 16 and flush with the same when lowered the forward end of said seat portion is recessed, as at 40, to provide a finger-hold for lifting the same.

Each seat portion or section 28 comprises a rectangular open frame 28^a, forming the lower part thereof, and a top or lid 28^b, the frame being hinged to the top rail 16 at the front of the bench with its opposite end fitting in a recess in the top rail at the rear of the bench and the lid connected by hinges 39 to said frame at the rear end thereof so as to swing upward at its forward end. These seat sections 28, 28, are hinged to the top of the bench in the same manner as the main seat section 26, and as the means for supporting the same in tilted position are exactly like those already described with reference to seat section 26 (see Fig. 6) the foregoing description of said means will apply, like numerals of reference being used. Likewise the front strip of the frame 28^a of each seat section 28 is recessed for a fingerhold 40, and in addition there is a recess 41 at the free end of the lid to provide a finger-hold for raising the same. As will be readily observed this construction for the seat sections 28 located over the music cabinets or compartments not only provides for full access to the compartments by lifting the lid 28^b and swinging it upward and backward to any extent desired but also provides for adjusting these sections to tilted position on a line with or independently of the center or 135

main seat section 26. Of course when all the adjustable seat sections are lowered the bench presents a plain top or straight seat, the hinges 39 being inset so as to provide a smooth surface.

The article of furniture herein shown and described is of pleasing appearance and any desirable changes may be made in ornamental finish or design, the essential features being to provide in connection with the bench cabinets or compartments to contain sheet music, &c., with provision for easy access to said compartments by a performer seated on the center seat section without rising therefrom, as well as providing for tilting the several seat sections as desired; for instance in playing duets said seat sections may all be tilted or inclined at the same angle so that the performers may sit side by side, as there is no perceptible gap between the seat portions.

I claim:—

1. A combined piano-bench and music cabinet comprising spaced apart box-like end portions forming compartments, a rectangular top frame connecting said end portions, an adjustable seat section within the frame intermediate the upper ends of the compartments, and lids for the compartments hinged within the top frame above said compartments and normally forming portions of the seat of the bench.

2. A combined piano-bench and music cabinet comprising spaced apart box-like end portions forming compartments, a rectangular top frame connecting said end portions, a vertical longitudinal partition connecting the box-like end portions below the top at the center thereof to provide opposite recesses below the center portion of the seat, a central seat portion over the partition, and lids hinged to the top frame above the compartments to normally form portions of the seat of the bench and provide access to the compartments, substantially as shown and for the purpose set forth.

3. A combined piano-bench and music cabinet comprising spaced apart box-like end portions forming compartments, a rectangular top frame connecting said end portions, a seat section within the top frame intermediate the compartments pivoted at one end so as to be tilted upward at the other end, and a rack-plate and pin for supporting said seat section at the desired inclination; together with lids hinged in the top frame at the upper end of the compartments to normally form portions of the seat of the bench and for access to the compartments, substantially as shown and for the purpose set forth.

4. A combined piano-bench and music cabinet comprising spaced apart box-like end portions forming compartments or music cabinets, a top connecting said end portions,

an adjustable seat portion within the top pivoted at one end, a pin projecting from the body of the bench, a rack-plate pivoted to the underside of the seat section to ride over the pin and engage the same when said seat section is raised, said rack-plate having a hooked stop at its outer end beyond the series of engaging-teeth, and a spring guide having a lateral member by which it is attached to one side of the rack-plate so that said guide will overlie the teeth, the outer end of the guide being curved inward to near the edge of the rack-plate between the series of teeth and hooked stop to guide the pin out of contact with the teeth when the seat section is lowered.

5. A combined piano-bench and music cabinet comprising spaced apart box-like end portions forming compartments or music cabinets, a rectangular top frame connecting said end portions, a seat section within the top frame intermediate the compartments and pivoted at one end, means for adjusting the inclination of said seat section, and a seat section covering each compartment including a frame pivoted at one end within the top frame, a lid hinged to the end of the seat frame opposite its pivoted end, and means for adjusting the inclination of the seat frame of said seat section, substantially as shown and described.

6. A combined piano bench and music cabinet comprising spaced apart box-like end portions forming compartments, a rectangular top frame connecting said end portions, a seat section intermediate the compartments pivoted at one end within the top frame, and seat sections covering the compartments, said last mentioned seat sections each comprising a frame pivoted at one end to the top frame and a lid hinged to the seat frame at the other end thereof, together with means for adjusting the several seat sections comprising rack-plates pivoted respectively to the center seat section and to the seat-frames of the end seat sections, and pins projecting from the body of the bench to engage the rack-plates, said rack-plates having a hooked stop at the outer end thereof and a spring guide cooperating with the stop to guide the pin out of contact with the teeth on the rack-plate when the seat section is lowered, substantially as herein shown and for the purpose set forth.

7. A piano bench and music cabinet comprising a compartment and a seat at one side of said compartment; together with an adjustable seat section closing the compartment consisting of an open frame connected to the upper end of said compartment, a lid in said frame providing access to the compartment independent of movement of said seat frame, and means engaging the frame for adjusting the inclination of the seat section.

8. A piano bench and music cabinet comprising a compartment and a seat at either side of said compartment, together with an adjustable seat section for the bench closing the compartment and consisting of an open frame in the upper end of the compartment hinged to the forward end thereof, a lid

hinged at one end to said frame to form the seat portion and provide access to the compartment independent of movement of said seat frame, and means engaging the seat frame for adjusting the inclination of the seat section.

GEORGE H. MERKEL.
